LEONARD TILTON, OF BROOKLYN, E. D., NEW YORK.

Letters Patent No. 65,304, dated May 28, 1867.

IMPROVEMENT IN DEVICE FOR TRANSMITTING MOTION.

The Schedule referred to in these Letters Patent and making part of the same.

TO ALL WHOM IT MAY CONCERN:

Be it known that I, LEONARD TILTON, of Brooklyn, E. D., Kings county, New York, have invented a new and improved Mechanical Device for Transmitting Motion; and I do hereby declare that the following is a full, clear, and exact description thereof, which will enable others skilled in the art to make and use the same, reference being had to the accompanying drawings, forming part of this specification.

This invention relates to a new and improved mechanical device for transmitting a reciprocating motion from a rotary shaft; and it consists in the employment or use of a belt-shipper in connection with a cam, an idle and working pulley, and gearing, all arranged to operate as hereinafter set forth. In the accompanying sheet of drawings—

Figure 1 is a side view of my invention.

Figure 2, a plan or top view of the same.

Similar letters of reference indicate corresponding parts.

A represents the frame of the machine, which may be constructed in any proper manner to support the working parts, and B is a shaft placed horizontally in one end of the frame, and having a toothed wheel, C, keyed upon one end of it, and a cam, D, keyed on the opposite end. This cam, in this instance, is composed of a spiral rib, a, on one side of a circular plate, b, as shown clearly in fig. 1. On the shaft B there is also keyed a toothed wheel, E, which gears into a pinion e, the latter gearing into a pinion, e $\times$, at one side of a pulley, F, said pinion and pulley being in one piece, if desired, and placed loosely on a shaft, G $\times$, in the frame A, and has a pinion, H, keyed on one end of it, which gears into the wheel C of shaft B. On the shaft G $\times$ there is also placed loosely a pulley, I, and a pulley, J, the latter being keyed or otherwise secured on the shaft. K is a belt, which works around a pulley, L, on a driving-shaft, M, and around any of the pulleys F I J, on the shaft G $\times$. And N N' represent the two arms of a belt-shipper, the upper arm N being secured by a pivot-belt, d, on the frame A, and the lower arm N' secured by a pivot, e, to a cross-bar, f, in the frame A. The upper arm N is provided with a pendent-pin, g, which passes through an oblong slot, h, in the lower arm N', and by this means motion is communicated from the upper to the lower arm. The upper arm N is provided with a loop, i', through which the belt passes, and the lower arm provided with a fork, j', between the prongs of which the belt passes, as shown in fig. 1. O is a bent lever on the frame A, one end of which is connected by a pivot, k, to the upper arm N of the belt-shipper, the opposite end extending out beyond the frame A and passing between adjustable pins P P on a bar, Q, which is fitted in guides l l, at one side of the frame A, and allowed to slide freely therein. This bar Q has a friction-roller, R, attached to one end of it, and this roller works in the groove formed by the spiral rib a, (see fig. 1.)

The operation is as follows: As the shaft M is rotated, motion is communicated to the shaft B by means of the belt K running over the pulley F or J. The shaft B and cam D are turned in the direction indicated by the arrow 1, through the medium of the gearing H C, and the bar Q moved in the direction indicated by arrow 2, and when the belt K is working over the pulley F the shaft B is turned in a reverse direction, as indicated by arrow 3, through the medium of the gearing e $\times$ e E, and the bar Q moved in the direction indicated by the arrow 4. The belt K is shipped from the pulley F to the pulley J, and *vice versa*, by the movement of the bar Q, the pins P P thereon acting against the lever O and moving the arms N N', the loose pulley I, serving to relieve the pulleys F J by causing the belt K to pass entirely off from one of said pulleys before it can act upon the other.

This invention is applicable to various machines in which it is required to communicate a reciprocating movement to a certain part from a rotary driving-shaft.

I claim as new, as far as my invention is now perfected—

The cam D and bar Q, in combination with the pulleys F I J, gearing H C e $\times$ e E, belt H, and belt-shipper composed of the arms N N', arranged and operated automatically from the bar Q, substantially in the manner as and for the purpose herein set forth.

LEONARD TILTON.
